BOX MAGAZINE FOR FIREARMS

Clifford H. Warner, New Haven, Conn., assignor
to Olin Industries, Inc., New Haven, Conn., a
corporation of Delaware

Application March 1, 1947, Serial No. 731,767

10 Claims. (Cl. 42—50)

1

The present invention relates to improvements in magazines for firearms and relates more particularly to improvements in the type of magazine known in the art as "box" magazines, i. e., magazines of box-like form which serve to hold a plurality of cartridges in side-by-side relationship rather than in end-to-end relationship as is the case with "tubular" magazines.

It has heretofore been the general practice to provide box-magazines with spring-pressed followers which extend transversely substantially entirely across the interior of the box-like housing and which have limited capacity for tilting to provide accommodation for changes in angle between a stack or column of rimmed or flanged cartridges and but one of such cartridges. Such prior magazines do not, therefore, effectively and reliably handle a large number of such cartridges as is required in modern repeating firearms.

One of the main objects of the present invention is to provide a superior box-magazine which will reliably and effectively hold and feed a plurality of cartridges.

A further object of the present invention is to provide a superior box-magazine which will effectively and reliably hold and feed a plurality of rimmed or flanged cartridges without jamming or otherwise malfunctioning.

Still another object of the present invention is to provide a superior box-magazine which will effectively hold and feed a greater number of rimmed or flanged cartridges than has been heretofore possible with standard box-magazines.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a top or plan view of a box-magazine embodying the present invention;

Fig. 2 is a view thereof in side elevation;

Fig. 3 is a reversed plan view thereof;

Fig. 4 is a view mainly in central longitudinal section on the line 4—4 of Fig. 1, but on a larger scale and with some of the parts left in elevation;

Fig. 5 is a transverse sectional view taken on the line 5—5 of Fig. 4;

Fig. 6 is a similar view taken on the line 6—6 of Fig. 4;

Fig. 7 is a perspective view of the cartridge-follower assembly;

2

Fig. 8 is a perspective view of the follower-body detached; and

Fig. 9 is a perspective view of the follower-arm detached.

5 The particular box-magazine chosen for illustration in the accompanying drawings in order to make clear a preferred form of the present invention, includes, in the main, a housing generally designated by the reference character 10, a cartridge-follower generally designated by the reference character 11 and a helical follower-spring 12.

10 The housing 10 may be conveniently formed of sheet metal and is of substantially-rectangular form in cross section and includes complementary opposite side walls 13 and 14 extending in parallelism with each other. The said housing also includes a substantially-flat rear wall 15 and a front wall 16.

15 The complementary side walls 13 and 14 extend in parallelism in a vertical direction but slope forwardly and inwardly toward each other in transverse section, as is especially well shown in Figs. 5 and 6. The forward portions of the re-

20 spective opposite side walls 13 and 14 are respectively integrally connected to the front wall 16 by curved portions 17 and 18 which are substantially semicircular in cross section and curve outwardly to form an integral longitudinal guide-

25 way 19 adjacent the front of the housing 10. The said semicircular portions 17 and 18 extend substantially the full length of the housing 10 and provide for the guidance of the follower 11 and follower-spring 12, in a manner as will more fully

30 hereinafter appear.

25 Slightly above its lower edge, the rear wall 15 of the housing 10 is formed with a transverse slot 20 which is in line with a similar slot 21 formed in the front wall 16. Removably installed in the

35 slots 20 and 21 just referred to is a bottom-plate 22 preferably tapering to correspond to the tapering form of the space defined by the side walls 13 and 14 and having at its rear end a laterally-offsetting finger 23 which extends downwardly adjacent the outer face of the rear wall 15 and provides for the convenient removal of the said bottom-plate when that is required.

40 As is indicated in Fig. 2, the side wall 14 of the housing 10 is outwardly struck adjacent its upper edge to provide a downwardly-facing retaining-abutment 24 which may be utilized to releasably retain the box-magazine in a firearm structure (not shown), in a manner common in the art.

45 At the cartridge-delivery end of the housing 10, the upper edges of the respective rear por-

tions of the side walls 13 and 14 are turned inwardly toward each other to provide a pair of head-retaining lips 25 and 26. The said lips 25 and 26 have their extremities spaced from each other a distance less than the diameter of both the body-portion 27 and the rim or flange 28 of cartridges such as are each generally designated by the reference character 29. The upper-inner extremities of the lips 25 and 26 are inclined forwardly and upwardly in parallelism with the extremities of a pair of complementary retaining-lips 30 and 31 respectively formed on the side walls 13 and 14. The space between the extremities of the retaining-lips 30 and 31 is greater than the space between the extremities of the head-retaining lips 25 and 26 and preferably is but slightly less than the diameter of the body-portion 27 of the cartridges such as 29, but sufficiently flexible to yield outwardly when slight force is applied thereto in either inserting or removing cartridges such as 29.

The head-retaining lips 25 and 26 and the retaining-lips 30 and 31 above referred to are, generally speaking, of a form well known in the art.

The follower 11 before referred to includes a follower-body generally designated by the reference character 32 and a follow-arm 33. The follower-body 32 includes a cylindrically-contoured head 34 and a similarly contoured stem 35 axially in line with the said head but smaller in diameter than the same. The said head 34 is of such diameter as to freely slide in the guideway 19, but to be restrained against appreciable tilting thereby.

Substantially at the junction of its head 34 and stem 35, the follower-body 32 is formed with a rearwardly-extending finger 36 slidably fitting between the adjacent portions of the complementary side walls 13 and 14. In its upper portion, the head 34 is formed with an upwardly-opening notch 37 extending in parallelism with the longitudinal axis of the finger 36. The said notch receives with a rocking fit the vertically-extending tail 38 integral with one end of the follower-arm 33. The said follower-arm 33 also includes a platform-portion 39 extending rearwardly over the finger 36 of the follower-body 32 and having a sliding fit between the adjacent portions of the side walls 13 and 14 of the housing 10.

A pivot-pin 40 extending transversely through the head 34 of the follower-body 32 and through the tail 38 of the follower-arm 33 serves to pivotally connect the said follower-arm to the said follower-body for swinging movement with respect thereto in a vertical plane. The forward lower portion of the tail 38, by its engagement with the adjacent portion of the bottom wall of the notch 37 in the follower-body 32, serves to limit the upward swinging movement of the platform-portion 39.

The rearwardly-extending finger 36 of the follower-body 32 is formed with an upwardly-facing spring-receiving socket 41 which receives and stabilizes the lower end of a helical compensating-spring 42. The upper portion of the compensating-spring 42 fits over a guide-pin 43 extending downwardly from the platform-portion 39 of the follower-arm 33 in substantial axial alignment with the spring-receiving socket 41.

Encircling the downwardly-extending stem 35 of the follower-body 32 is the upper end of the helical follower-spring 42 located and guided in the guideway 19 in the housing 10 and having its lower end resting upon the upper face of the

forward portion of the removable bottom-plate 22 of the said housing. The said follower-spring exerts a constant but yielding effort to move the entire cartridge-follower 11 upwardly toward the cartridge-delivery end of the housing 10 to maintain the uppermost of the column of cartridges 29 against the head-retaining lips 25 and 26 of the housing 10.

Assuming that the housing 10 is loaded substantially to its capacity with rimmed or flanged cartridges like 29, as is indicated by broken lines in Fig. 4, it is to be noted that the height of the rear portion of such column exceeds the height of the forward portion of such column due to the rims or flanges 28. Under these conditions, the lowermost cartridge of the column will rest upon the platform-portion 39 of the follower-arm 33 and will cause the said follower-arm to be inclined relatively steeply rearwardly and downwardly. Since the particular housing shown is wider at its rear than at its front, the head-ends of the cartridges 29 will be able to swing slightly sidewise and thus avoid an excessive change of angle of the follower-arm 33 between its uppermost and its lowermost positions.

Now, as the cartridges 29 are sequentially removed from the upper or cartridge-delivery end of the housing 10 (usually by the breech-bolt of a firearm), the inclination of the said follower-arm will gradually lessen as the said column of cartridges becomes shorter and shorter, all as will be apparent by comparing the broken-line showing of the follower-arm 33 and the full-line showing thereof in Fig. 4.

By means of a construction and arrangement of parts exemplified in the accompanying drawings, the follower 11 will automatically accommodate itself to an exceedingly-high column of flanged or rimmed cartridges or to a single cartridge without occasioning binding or other malfunctioning of the parts.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A box-magazine, including in combination: a box-like housing having an open cartridge-delivery end and provided interiorly adjacent one of its longitudinal end walls with a longitudinal guide-means of greatly-less cross-sectional area than the interior cross-sectional area of the housing as a whole; a cartridge-follower in the interior of the said housing and slidably lengthwise thereof, the said cartridge-follower including a follower-body having a guide-portion slidably with respect to the longitudinal guide-means in the said housing, the said cartridge-follower also having a follower-arm pivoted to the said follower-body and projecting therefrom toward the longitudinal side wall of the housing which is opposite the side wall adjacent the said guide-means; the said follower-arm being positioned to provide a tilting platform for a column of cartridges within the said housing, the said cartridge-follower also being provided with spring-means urging the free end of the said follower-arm to swing relative to the said follower-body toward the cartridge-delivery end of the said housing; and second spring-means

urging the cartridge-follower bodily toward the cartridge-delivery end of the said housing.

2. A box-magazine, including in combination: a box-like housing having an open cartridge-delivery end and provided interiorly adjacent one of its longitudinal end walls with a longitudinal guide-means of greatly-less cross-sectional area than the interior cross-sectional area of the housing as a whole; a cartridge-follower in the interior of the said housing and slidable lengthwise thereof, the said cartridge-follower including a follower-body having a guide-portion slidable with respect to the longitudinal guide-means in the said housing, the said cartridge-follower also having a follower-arm pivoted to the said follower-body and projecting therefrom toward the longitudinal side wall of the housing which is opposite the side wall adjacent the said guide-means, the said follower-arm being positioned to provide a tilting platform for a column of cartridges within the said housing, the said cartridge-follower also being provided with spring-means urging the free end of the said follower-arm to swing relative to the said follower-body toward the cartridge-delivery end of the said housing; and second spring-means engaged with and guided by the aforesaid guide-means and urging the cartridge-follower bodily toward the cartridge-delivery end of the said housing.

3. A box-magazine, including in combination: a box-like housing having an open cartridge-delivery end and provided interiorly adjacent one of its longitudinal end walls with a longitudinal channel-like guideway of greatly-less cross-sectional area than the interior cross-sectional area of the housing as a whole; a cartridge-follower in the interior of the said housing and slidable lengthwise thereof, the said cartridge-follower including a follower-body having a guide-portion slidable in the longitudinal guideway in the said housing, the said cartridge-follower also having a follower-arm pivoted to the said follower-body and projecting therefrom toward the longitudinal side wall of the housing which is opposite the side wall adjacent the said guideway, the said follower-arm being positioned to provide a tilting platform for a column of cartridges within the said housing, the said cartridge-follower also being provided with spring-means urging the free end of the said follower-arm to swing relative to the said follower-body toward the cartridge-delivery end of the said housing; and second spring-means urging the cartridge-follower bodily toward the cartridge-delivery end of the said housing.

4. A box-magazine, including in combination: a box-like housing having an open cartridge-delivery end and provided interiorly adjacent one of its longitudinal end walls with a longitudinal channel-like guideway of greatly-less cross-sectional area than the interior cross-sectional area of the housing as a whole; a cartridge-follower in the interior of the said housing and slidable lengthwise thereof, the said cartridge-follower including a follower-body having a guide-portion slidable in the longitudinal guideway in the said housing, the said cartridge-follower also having a follower-arm pivoted to the said follower-body and projecting therefrom toward the longitudinal side wall of the housing which is opposite the side wall adjacent the said guideway, the said follower-arm being positioned to provide a tilting platform for a column of cartridges within the said housing, the said car-

tridge-follower also being provided with spring-means urging the free end of the said follower-arm to swing relative to the said follower-body toward the cartridge-delivery end of the said housing; and second spring-means located in and guided by the channel-like guideway in the housing and urging the cartridge-follower bodily toward the cartridge-delivery end of the said housing.

10. 5. A box-magazine, including in combination: a box-like housing having an open cartridge-delivery end and provided interiorly adjacent one of its longitudinal end walls with a longitudinal channel-like guideway of greatly-less cross-sectional area than the interior cross-sectional area of the housing as a whole; a cartridge-follower in the interior of the said housing and slidable lengthwise thereof, the said cartridge-follower including a follower-body having an upwardly-opening notch and a guide-portion slidable in the longitudinal guideway in the said housing, the said cartridge-follower also having a follower-arm extending at one end into the upwardly-opening notch in the said follower-body and pivoted therein, the said follower-arm projecting from the said follower-body toward the longitudinal side wall of the housing which is opposite the side wall adjacent the said guideway, the said follower-arm being positioned to provide a tilting platform for a column of cartridges within the said housing, the said cartridge-follower also including spring-means urging the free end of the said follower-arm to swing relative to the said follower-body toward the cartridge-delivery end of the housing; and second spring-means urging the cartridge-follower bodily toward the cartridge-delivery end of the said housing.

6. A box-magazine, including in combination: 40 a box-like housing having an open cartridge-delivery end and provided interiorly adjacent one of its longitudinal end walls with a longitudinal channel-like guideway of greatly-less cross-sectional area than the interior cross-sectional area of the housing as a whole; a cartridge-follower in the interior of the said housing and slidable lengthwise thereof, the said cartridge-follower including a follower-body having an upwardly-opening notch and a guide-portion slidable in the longitudinal guideway in the said housing, the said cartridge-follower also having a follower-arm extending at one end into the upwardly-opening notch in the said follower-body and pivoted therein, the said follower-arm projecting from the said follower-body toward the longitudinal side wall of the housing which is opposite the side wall adjacent the said guideway, the said follower-arm being positioned to provide a tilting platform for a column of cartridges within the said housing, the said cartridge-follower also including spring-means urging the free end of the said follower-arm to swing relative to the said follower-body toward the cartridge-delivery end of the housing; and second spring-means located in and guided by the channel-like guideway in the said housing and urging the cartridge-follower bodily toward the cartridge-delivery end of the said housing.

7. A box-magazine, including in combination: 70 a box-like housing having an open cartridge-delivery end and provided interiorly adjacent one of its longitudinal end walls with a longitudinal channel-like guideway of greatly-less cross-sectional area than the interior cross-sectional area of the housing as a whole; a cartridge-follower

in the interior of the said housing and slidable lengthwise thereof, the said cartridge-follower including a follower-body having a guide-portion slidable in the longitudinal guideway in the said housing and a laterally-projecting finger, the said cartridge-follower also having a follower-arm pivotally connected at one end to the said follower-body and projecting from the said follower-body over the finger of the follower-body and toward the longitudinal side wall of the housing which is opposite the side wall adjacent the said guideway, the said follower-arm being positioned to provide a tilting platform for a column of cartridges within the said housing, the said cartridge-follower also including a helical spring interposed between the said finger and the follower-arm and urging the free end of the said follower-arm to swing relative to the said follower-body toward the cartridge-delivery end of the housing; and a second helical spring urging the cartridge-follower bodily toward the cartridge-delivery end of the said housing.

8. A box-magazine, including in combination: a box-like housing having an open cartridge-delivery end and provided interiorly adjacent one of its longitudinal end walls with a longitudinal channel-like guideway of greatly-less cross-sectional area than the interior cross-sectional area of the housing as a whole; a cartridge-follower in the interior of the said housing and slidable lengthwise thereof, the said cartridge-follower including a follower-body having a guide-portion slidable in the longitudinal guideway in the said housing and a laterally-projecting finger, the said cartridge-follower also having a follower-arm pivotally connected at one end to the said follower-body and projecting from the said follower-body over the finger of the latter and toward the longitudinal side wall of the housing which is opposite the side wall adjacent the said guideway, the said follower-arm being positioned to provide a tilting platform for a column of cartridges within the said housing, the said cartridge-follower also including a helical spring interposed between the said finger and the follower-arm and urging the free end of the said follower-arm to swing relative to the said follower-body toward the cartridge-delivery end of the housing; and a second helical spring located in and guided by the channel-like guideway in the said housing and urging the cartridge-follower bodily toward the cartridge-delivery end of the said housing.

9. A box-magazine, including in combination: a box-like housing having an open cartridge-delivery end and provided interiorly adjacent one of its longitudinal end walls with a longitudinal channel-like guideway of greatly-less

cross-sectional area than the interior cross-sectional area of the housing as a whole; a cartridge-follower in the interior of the said housing and slidable lengthwise thereof, the said cartridge-follower including a follower-body slidable in the guideway in the said housing and having an upwardly-opening notch and a laterally-projecting finger, the said cartridge-follower also having a follower-arm extending over the said finger and pivoted at one end in the upwardly-opening notch in the said follower-body, the said follower-arm projecting from the said follower-body toward the longitudinal side wall of the housing which is opposite the side wall adjacent the said guideway, the said follower-arm being positioned to provide a tilting platform for a column of cartridges within the said housing, the said cartridge-follower also including a helical spring interposed between the said finger and the follower-arm and urging the free end of the latter to swing relative to the said follower-body toward the cartridge-delivery end of the housing; and a second helical spring urging the cartridge-follower bodily toward the cartridge-delivery end of the said housing.

10. A box-magazine, including in combination: a box-like housing having an open cartridge-delivery end and provided interiorly adjacent one of its longitudinal end walls with a longitudinal channel-like guideway of greatly-less cross-sectional area than the interior cross-sectional area of the housing as a whole; a cartridge-follower in the interior of the said housing and slidable lengthwise thereof, the said cartridge-follower including a follower-body slidable in the guideway in the said housing and having an upwardly-opening notch and a laterally-projecting finger, the said cartridge-follower also having a follower-arm extending over the said finger and pivoted at one end in the upwardly-opening notch in the said follower-body, the said follower-arm projecting from the said follower-body toward the longitudinal side wall of the housing which is opposite the side wall adjacent the said guideway, the said follower-arm being positioned to provide a tilting platform for a column of cartridges within the said housing, the said cartridge-follower also including a helical spring interposed between the said finger and the said follower-arm and urging the free end of the latter to swing relative to the said follower-body toward the cartridge-delivery end of the housing; and a second helical spring located in and guided by the channel-like guideway in the said housing and urging the cartridge-follower bodily toward the cartridge-delivery end of the said housing.

CLIFFORD H. WARNER.
